UNITED STATES PATENT OFFICE.

CARL T. WEIBEZAHN, OF ST. PETER, MINNESOTA, ASSIGNOR TO FORT DEARBORN WATCH & CLOCK COMPANY, OF CHICAGO, ILLINOIS, A CORPORATION OF ILLINOIS.

DESIGN FOR A BOOK-DISPLAY STAND.

Application filed July 16, 1921. Serial No. 485,295. Term of patent 3½ years.

To all whom it may concern:

Be it known that I, CARL T. WEIBEZAHN, a citizen of the United States, residing at St. Peter, county of Nicollet, and State of Minnesota, have invented a new, original, and ornamental Design for a Book-Display Stand, of which the following is a specification, reference being had to the accompanying drawing, forming a part thereof.

Fig. 1 is a side elevation of the stand, and Fig. 2 is a front elevation thereof.

What I claim and desire to secure by Letters Patent, is:—

The ornamental design for a book display stand, as shown.

Signed at Chicago, Cook County, Illinois, this 29 day of June, A. D. 1921.

CARL T. WEIBEZAHN.
